ANTI-GLARE VISOR FOR AUTOMOBILE OR THE LIKE

Albert Rothgart, Brooklyn, N.Y., assignor to Visionade Manufacturing Co., Inc., Brooklyn, N.Y., a corporation of New York

Filed Apr. 10, 1961, Ser. No. 64,671

Term of patent 7 years

(Cl. D14—6)

FIG. 1 is a top plan view of an anti-glare visor for automobiles or the like, embodying the invention;

FIG. 2 is an enlarged cross-sectional view taken on line 2—2 of FIG. 1 with portions shown omitted for convenience of illustration;

FIG. 3 is an enlarged fragmentary cross-sectional view taken on line 3—3 of FIG. 1; and

FIG. 4 is an enlarged fragmentary cross-sectional view taken on line 4—4 of FIG. 1.

I claim:

The ornamental design for an anti-glare visor for automobiles or the like, substantially as shown.
